UNITED STATES PATENT OFFICE.

WILLIAM M. REMINGTON, OF SPRINGFIELD, MASSACHUSETTS, ASSIGNOR TO STEVENS-DURYEA COMPANY, OF CHICOPEE FALLS, MASSACHUSETTS, A CORPORATION OF MASSACHUSETTS.

WATER-PUMP FOR AUTOMOBILES.

1,100,327.

Specification of Letters Patent. Patented June 16, 1914.

Application filed January 10, 1913. Serial No. 741,226.

To all whom it may concern:

Be it known that I, WILLIAM M. REMINGTON, a citizen of the United States, residing at Springfield, in the county of 5 Hampden and State of Massachusetts, have invented certain new and useful Improvements in Water-Pumps for Automobiles, of which the following is a specification.

This invention relates to improvements 10 in water pumps for automobiles, and has for its object to provide an improved form of pump for use in circulating the water used for cooling the engine.

Another object of the invention is to provide 15 an improved form of bearings for such pump.

Still another object is to provide an improved means for cooling the bearings and maintaining them in a comparatively cooled 20 state.

It has been the practice hitherto in connection with such pumps to provide one or more grease cups for lubrication of the shaft and bearings. Owing to the high speed at 25 which such pump operates and to the ordinary heated temperature of the water, grease or oil lubrication has not been found to be satisfactory.

By my improved invention I have provided 30 a construction which enables the cooling and lubrication of the bearings by the water or other cooling fluid which is circulated by the water pump.

Other objects of the invention will be 35 made apparent and set forth in the following specification and accompanying drawings, in which—

Figure 1 is a side elevation of my improved pump. Fig. 2 is a sectional view 40 thereof, taken on the line 2—2 of Fig. 1. Fig. 3 is a detail section, taken along the line 3—3 of Fig. 1. Fig. 4 is a detail section, taken along the line 4—4 of Fig. 2; and Fig. 5 is a perspective detail view of 45 one of the bearings.

Like numerals refer to like elements throughout the drawings.

My improved pump comprises a main section 50 designated by the numeral 10, and a cover section designated by the numeral 11, the latter being provided with the offset peripheral portion 12 secured by the bolts or studs 13 to the flange portion 14 of the casing 10, which is of conventional shape and provided with the usual peripheral outlet

15 gradually increasing in cross section from the starting point on the periphery of the casing to the tangential portion 16 terminating in a coupling flange, as shown in Fig. 1. The casing is provided with an outwardly 60 extending hub portion 18, constructed with an intake chamber 19 therein, with which communicates the intake 20, as shown in Figs. 1 and 2. Adjacent its extremity this hub portion is provided with a reduced end 65 21, in which is mounted the bearing 22, having the collar portion 23 abutting against the shoulder 24, as shown in Fig. 2. Outwardly of the bearing 22 in the reduced hub portion 21 is a chamber 25.

A duct or tube 26 leads from the interior 70 of the intake 20 to the interior of the chamber 25, as shown in Figs. 1 and 2. The bearing 22 is provided with longitudinal grooves 27 in its inner surface. Outwardly 75 extending grooves 28, communicating with grooves 27, are provided in the outer end of the collar 23, as shown most clearly in Fig. 5.

The cover portion 11 of the casing is provided 80 with an outwardly extending hub portion 30, externally threaded, as indicated at 31. Interiorly of this hub portion is mounted the bearing 32, somewhat similar to the bearing 22, shown of greater length and inwardly inclined, as indicated at 33 at its outer extremity. This bearing 32 is provided with longitudinal grooves 34 in its inner periphery, communicating with outwardly extending grooves 35 in the outer 90 face of the collar portion 36. At the opposite extremity of the grooves 34 is a peripheral groove 37 communicating with the longitudinal grooves, as shown in Fig. 4.

A shaft 40 is mounted transversely of 95 the hub casing of the pump and is mounted adjacent its extremities in the bearings 22 and 32, as shown in Fig. 2. This shaft is centrally apertured, as indicated by the numeral 41, and has one end terminating inwardly of the end of the reduced hub portion 21. The aperture 41 in the shaft 40 is in communication with the chamber 25 at one extremity and at its other extremity communicates with the cross aperture 42 in 100 the shaft 40, this cross aperture communicating and being held in alinement with the peripheral groove 37.

The propeller wheel 45 of the pump is 105 provided with the usual vanes 46 and with 110

an apertured sleeve 48 securely fitting around the shaft 40, to which it is suitably secured by a taper pin 47, etc. This sleeve is provided adjacent its forward portion, as shown in Fig. 2, with a bearing 49 abutting against the end of the bearing 32, and at its other extremity is provided with a bearing 50 abutting against the bearing 22.

This construction of the bearings and propeller wheel serves to reduce friction at the points of contact, and also provides for maintaining the propeller and shaft against relative rotation with respect to the fan and pump casing. A stuffing box cap 51 is threaded over the end of the hub portion 30 and has the usual inturned end portion 52, through which projects the shaft 22 and which serves to press against and expand the stuffing or packing 53 to provide a water-tight joint, as shown.

The operation of the pump is similar to that of the ordinary centrifugal pump, the rotation of the shaft causing rotation of the impeller, which causes water or other fluid to be drawn in through the intake and forces it out through the peripheral outlet. Owing to the close proximity of the disk 45 to the cover plate 11 and to the adhesive and cohesive properties of the water the rotation of the impeller gives rise to a pumping action and the creation of a region of low pressure between said disk and said plate. As a result of this action, together with the suction acting toward the intake chamber 19, a portion of the water delivered through the intake will be transmitted by or drawn through the small tube or duct 26 to the chamber 25, from whence a portion of it will flow through the grooves 27 in the bearing 22, and out through the end grooves 28 into the intake chamber 19. This will serve to preserve the temperature of bearing 22 at a comparatively low point and will prevent overheating thereof.

The portion of the water delivered to the chamber 25 passes by virtue of the action of the low pressure between the disk 45 and the cover plate 11, through aperture 41 in the shaft 40 to cross aperture 42, whence it is delivered to the annular groove 37 and is discharged through the grooves 34 in the bearing 32, and outwardly through the end grooves 35 into the space between the front portion of the propeller and the casing cover, as shown in Fig. 2. This provides for the cooling and lubrication of the bearing 32.

It will be apparent that in the operation of my improved pump I have provided for the reduction of friction between the propeller mounting and the bearings by the provision of the bearings 49 and 50. It will further be apparent that by circulating a certain amount of the engine cooling fluid, as shown and described, the bearings will be

suitably lubricated and will also be sufficiently cooled, and the amount of cooling fluid passing therethrough will be proportional to the speed of the impeller and shaft, which will therefore provide for increased cooling and lubrication in proportion to the increase in speed, which is a point much to be desired in high speed operation of a pump of this type. Furthermore, an added advantage is that since all the water used for lubrication and cooling is ultimately delivered to the impeller for discharge, no reduction in efficiency of the operation of the pump will result.

While I have shown and described my invention with more or less particularity, I do not wish to be unduly restricted thereto beyond the scope of the appended claims.

What I claim is:

1. In a device of the class described, a casing, a shaft journaled in bearings in said casing, and means contained within said shaft, bearings and casing to supply cooling fluid to said shaft and bearings.

2. In a device of the class described, a casing, a shaft journaled in bearings in said casing, an intake leading from said casing, and means contained within said shaft, bearings and casing to supply cooling fluid from said intake to said shaft and bearings.

3. In a device of the class described, a casing, said casing being provided with outwardly projecting hub portions; an intake communicating with the interior of said casing, and an auxiliary duct leading from said intake to one of said hub members.

4. In a device of the class described, a casing, said casing being provided with outwardly projecting hub portions, one of said hub portions being closed at its end and provided with an interiorly located chamber adjacent the end thereof, an intake communicating with the interior of said casing, and an auxiliary duct leading from said intake to said chamber in said hub portion.

5. In a device of the class described, a casing, said casing being provided with outwardly projecting hub portions, one of said hub portions being closed at its end and provided with an interiorly located chamber adjacent the end thereof, an intake communicating with the interior of said casing, an auxiliary duct leading from said intake to said chamber in said hub portion, and a bearing mounted in said hub portion, said bearing being provided with grooves communicating at one end with said chamber and leading from said chamber to the interior of said casing.

6. In a device of the class described, a casing, said casing being provided with outwardly projecting hub portions, one of said hub portions being provided with an interiorly located chamber adjacent one end thereof, bearings in said hub portions, an

intake communicating with said casing, a duct leading from said intake to the interior of said chamber, and a shaft mounted in said bearings, said shaft being apertured and communicating thereby with said chamber.

7. In a device of the class described, a casing, said casing being provided with outwardly projecting hub portions, an interiorly located chamber adjacent one of said hub portions, an intake communicating with said casing, a duct leading from said intake to said chamber, bearings mounted in each of said hub portions, the bearing adjacent said chamber being provided with grooves in its interior periphery and at its end, said grooves being in communication with said chamber, a shaft rotatably mounted in said bearings, said shaft being centrally apertured and said aperture communicating with said chamber at one extremity and with a cross aperture in said shaft at its other extremity, said bearing adjacent the last named extremity being provided with an annular peripheral groove in communication with said cross aperture in said shaft and with longitudinal grooves leading from said annular groove to and communicating with

outwardly extending grooves in said bearing.

8. In a device of the class described, a casing, said casing being provided with an outwardly extending hub portion on each side thereof, bearings mounted in said hub portion, said bearings being provided with an outwardly extending collar portion at their inner extremity, a shaft rotatably mounted in said bearings, and an impeller provided with a sleeve, said sleeve being mounted on and secured to said shaft and being provided with bearings at each end thereof, said bearings abutting against and being held between the collar portions of said first-named bearings.

9. In a device of the class described, a casing, a shaft journaled in bearings in said casing, an intake leading to said casing, and means to supply cooling fluid directly from said intake to said shaft and bearings.

In testimony whereof, I have subscribed my name.

WILLIAM M. REMINGTON.
